SHOE RACK

Paul S. MacMichael, Seattle, Wash.

Application September 19, 1935, Serial No. 41,237

8 Claims. (Cl. 12—128.1)

This invention relates to shoetrees and racks therefor, adapted for use generally as a working combination.

Some of the objects of my invention are to provide a simply constructed shoe tree which may be workably mounted on a suitable rack adapted to carry a plurality of such trees compactly spaced with the treed shoes preferably occupying a generally vertical position with their soles and heels adjacent a supporting wall, and, to be able to maintain said position without the use of springs. The rack also serves to prevent undesirable contact between treed shoes and clothes which may be nearby.

Other objects are to have a mounted shoetree flexibly or pivotally movable to facilitate the operation of treeing a shoe thereon, said movement first bringing said tree into a relatively non-interfering treeing position in respect to adjacent closely spaced trees and the supporting wall; and second, providing for the easy free shifting of their relative angular positions as said shoe is brought into position on said tree, a detachably mounted tree being provided so that any rack may readily be equipped with trees of any desired size.

My invention also consists in certain new and original features of construction and combination of parts as hereinafter set forth and claimed.

Although the novel features which are believed to be characteristic of this invention will be particularly pointed out in the claims appended hereto, the invention itself, as to its objects and advantages, and the manner in which it may be carried out, may be better understood by reference to the accompanying drawing forming a part thereof, in which—

Fig. 1 is a perspective view of the shoetree and rack combination with one shoe in place thereon.

Fig. 2 is a vertical cross-section on the line 2—2 of Fig. 1.

Fig. 3 is a vertical cross-section on the line 3—3 of Fig. 1 showing a treed shoe.

Fig. 4 is an enlarged perspective of a detail of construction.

Fig. 5 is a cross-section on the line 5—5 of Fig. 4.

Fig. 6 is similar to Fig. 5 with the axle in dotted line.

Like reference characters denote like parts in the various figures of the drawing.

In the drawing accompanying and forming part of this specification certain specific disclosure of the invention is made for the purpose 55 of explanation; but it will be understood that

the details may be modified in various respects without departing from the broad spirit of the invention.

Referring to the drawing, a shoetree 1 has a toe piece 2, a heel piece 3, and a flexible resilient shank 4 shown in its free form at 4a (see Fig. 2) and its flexed form at 4b (see Fig. 3). Said shank 4 has formed in it a resilient hub 5 provided with an expansible opening 6 whereby it can be snapped onto the supporting axle 7. Said hub 5 is shown in its free form in Fig. 6 having an axial diameter in the space 8 somewhat less than the diameter of the axle 7 so that when the hub 5 is in expanded position on said axle 7 (see Fig. 5) it grips said axle with an elastic spring pressure tending frictionally to resist relative rotational movement on said axle 7.

Opposite the hub opening 6 is an elongated hub part 9 which provides for a greater range of resilient expansion affecting the hub opening 6, and also by breaking the continuity of contact between the hub 5 and the axle 7 prevents an excessive frictional resistance such as is obtained in the well-known circular brake band.

With the tree shank 4 in the unflexed position 4a (see Fig. 2), the resilient hub pressure on the axle 7 is only that due to the spring pressure naturally developed in the hub itself, and is ample to support the tree 1 stationary in a predetermined position as shown in Fig. 2. When the shank 4 is flexed to the position 4b (see Fig. 3) the gripping action of the hub 5 on the axle 7 is increased due to the pressure in the flexed shank 4 tending to close the hub opening 6 and thereby is provided a useful additional gripping effect aiding in the support of the treed shoe in its normal position adjacent the wall 16 (see Fig. 3).

Said axle 7 has a reduced diameter 12 near each end (see Fig. 1) for the passage thereover of the hub 5 with less forced expansion than would otherwise be required, said hub 5 with the tree 1 then being moved along the axle 7 to its spaced position thereon to be held longitudinally in said position by the snap rings 13 placed on the axle 7 and resiliently gripping said axle on each side of each hub 5 thereon. The rack 14 as a whole, preferably made in a single piece, comprises an axle 7, adapted to support a plurality of trees 1, carried by the angle wall brackets 15 and may be screwed on a supporting wall 16.

The toe piece 2 having a cross-sectional shape generally like its rear end 21 has a bottom 22 with a forward "sled-runner" curved part 23 adapting it to glide readily into a shoe 31.

With the hub resiliently gripping the axle 7, the tree 1 is normally supported in any predetermined angular position in which it may be placed, relative to the axle 7, which position for the empty tree may suitably be that shown in Fig. 2.

To tree a shoe, the tree will be rotated to the general position 32 (see Fig. 2) and the shoe 31 placed thereon so the parts occupy the general position indicated at 31a (see Fig. 3). The tree shank 4 is flexed as at 4b when in the shoe. The tree 1 is then manually rotated back to its normal shoe-carrying position (see Fig. 3), the shoe heel 33 being moved on the arc 34 until the shoe sole 35 is adjacent the wall 16, in which position it will then be supported by said frictional gripping effect.

The axle 7 is spaced out from the wall a distance adapted to permit of a limited rotation of a treed shoe in the manner described, said treed shoe normally occupying the space generally between said wall 16 and the line 17 passing vertically through said axle 7.

For removing a shoe substantially the reverse of the above operation takes place, the shoe on the tree being rotated forward toward a generally horizontal position, the shoe being removed and the tree then preferably being manually rotated to the position in Fig. 3.

Some of the novel features and advantages of my invention will now be pointed out.

In order to provide a compact storage in the limited space generally available, the shoe trees are mounted on a rack in spaced positions and normally are preferably to be held with their toe pieces close to the wall. Such close compact spacing makes it impractical to tree or de-tree shoes conveniently from immovable trees and especially when they are to be treed in the preferred position with the soles of the shoes toward the wall and close thereto. I have therefore devised a tree adapted to be movably carried on a support so that each tree independently may be moved or rotated into an accessible convenient treeing position practically non-interfering as regards the supporting wall or any shoes on adjacent trees, for which purpose a pivotal mounting of the tree is useful whether the axis of said pivot is generally parallel to the depth of a shoe in place or parallel to its width, or at some other angle thereto.

During the act of treeing a shoe, various parts of, or places on said tree will assume constantly changing angles relative to its other parts and also relative to the shoe being placed thereon. Where the user, with one hand, is handling a tree detached from any rack, and is handling a shoe with his other hand, these constantly changing relative angles are readily accommodated manually. If a tree is rigidly mounted at some point thereof in fixed position on a rack, it becomes an inconvenient and awkward operation to tree a shoe on account of said rigid mounting, but I have discovered that by mounting a tree pivotally on an axis generally parallel to the shoe width of said tree, a shoe may easily and conveniently be treed thereon.

In my preferred construction therefor, I use a tree mounted with its hub having a rotational axis generally parallel to the width of a treed shoe as aforesaid, said axis being positioned to pass across the shoe upper near its heel end. When the shoe is thus treed to rotate freely on said axis, the shoe sole and heel or shoe bottom will gravitate to a generally inclined plane at an angle about half-way between the vertical and

the horizontal. To cause the treed shoe to remain in a generally vertical position in which it may be placed adjacent the wall, I provide a frictional pivotal mounting or hub on the tree which elastically grips the supporting axle, said gripping effect being automatically increased by the pressure of the shank 4 when a shoe is treed on said tree. My preferred shoetree is provided with a one-piece flexible resilient shank 4 in which said resilient hub 5 is formed. The circumferential opening 6 in said hub permits of its elastic expansion relative to its axial diameter 8, and also provides for transmission of pressure along the shank 4 into said hub, and further provides means for readily snapping said hub onto the axle 7.

The toe-piece, I provide with a curved up "sled-runner" forward bottom part adapted to be passed into a shoe with a gliding action rather than tending to dig into the insole.

The tree as a whole is simple in construction and is adapted for use in combination with my rack or for ordinary detached use.

The shoetree rack is adapted to carry a plurality of pivotally mounted trees in spaced position and in combination with the snap ring collars 13 mounted thereon, to provide means for maintaining the spaced position of said trees. The rack axle serves as a protection to prevent adjacent clothes from contacting with treed shoes. I have referred to a wall as a convenient place for supporting my rack, a door also being appropriate but the rack or its axle only may be suspended or carried non-rotatably from any available supporting means by obvious appropriate modifications.

While I have shown and described a preferred construction for a shoetree and rack combination, I have found that the various details may be modified in various ways and still fall within the broad spirit of my invention and I wish to maintain all my rights to such modifications limited only as set forth in the claims appended herewith.

For instance, the hub 5 may be made as a separate part adapted for the attachment thereto of a shoetree. Different designs of shoetrees may be used in the general mode herein set forth. The device may be arranged on similar principles to support the treed shoe either with the heel up or with the toe up, or the treed shoe may be supported at some other than the generally vertical angle herein described as preferable. In various places herein, I use terms such as "pivotal" mounting, "hub" and "axle." These terms all relate to a construction wherein a pin, shaft or pivot engages with a generally encircling bearing or hub, providing for relative rotary motion about a generally fixed axial line. In principle, whether the hub part is on the stationary or the movable part, relative to the axle being on the other engaging part, is a matter of obvious mechanical equivalent. By appropriate modification to the arrangement herein shown to bring the pivotal axis closer to a vertical line through the center of gravity of the treed positioned shoe, the frictional positioning means may be made less strong and still serve its purpose. These and other modifications or variations of the principles of my invention are intended to be covered in my claims.

I claim:

1. In a shoe rack, the combination of a supporting member, a shoetree pivotally mounted thereon, said shoetree having a heel piece, a toe

piece and a shank connecting them, said shank having thereon a friction member which provides the pivotal mounting and the means for holding the shoetree in a predetermined position.

5. 2. In a shoe rack, the combination of a supporting member, a shoetree pivotally mounted thereon, said shoetree having a heel piece, a toe piece and a shank connecting them, said shank having formed therein a friction member which provides the pivotal mounting and the means for holding the shoetree in a predetermined position.

10. 3. In a shoe rack, the combination of a shoe-tree device, a hub attached to said tree for its pivotal support, a supporting non-rotating axle for said tree, and means for establishing a frictional engagement between said tree and said axle whereby they will maintain a manually established relative rotary position substantially independent of gravitational pull.

15. 4. In a shoe rack, the combination of a shoe-tree device comprising a toe piece, a heel piece, and a shank connecting said pieces with a hub formed in said shank for its pivotal support, a supporting non-rotating axle for said shank hub, and means for establishing a frictional engagement between said hub and said axle whereby they will maintain a manually established relative rotary position substantially independent of gravitational pull.

20. 5. In a shoe rack, the combination of a supporting shaft, and a shoetree, comprising a toe piece, a heel piece, and a flexible resilient shank adapted to maintain pressure between said toe and heel pieces with a shoe tread thereon, having a resilient open loop hub formed therein adapted for resilient frictional pressure on said supporting shaft, all said parts of said tree being

so arranged that treeing a shoe thereon stresses said resilient shank thereby increasing the resilient pressure tending to close said open loop hub and increasing its frictional resistance to relative rotary motion on said supporting shaft.

5. 6. A shoetree and rack combination comprising a supporting axle, a shoetree with a pivotal hub generally fitting said axle, a narrow opening through one side leading to the center of said hub, a part of said axle of reduced cross-section adapted to pass through said narrow hub opening whereby said hub may be brought into working position on said axle, and means for maintaining said longitudinal position.

10. 7. A shoetree and rack combination comprising a supporting axle, a shoetree with a pivotal hub generally fitting said axle, a narrow opening through one side leading to the center of said hub, a part of said axle of reduced cross-section adapted to pass through said narrow hub opening whereby said hub may be brought into working position on said axle, and means for maintaining said longitudinal position comprising a slightly open resilient ring adapted to grip said axle adjacent said longitudinally positioned tree.

15. 8. A shoetree comprising a toe piece and a heel piece directly connected by a resilient shank piece, and a resilient part thereon which provides for the pivotal mounting of said tree on an axle whereon the tree may be held in a predetermined position by resilient pressure exertable by said resilient mounting member, said member having a generally encircling form extending for substantially more than a one half circle for retaining engagement with an axle and being provided with an expansible circumferential opening leading into said generally encircled space.

20. 25. 30. 35. PAUL S. MACMICHAEL.
